UNITED STATES PATENT OFFICE.

RAYMOND A. BECKWITH, OF MILWAUKEE, WISCONSIN, ASSIGNOR TO KOEHRING COMPANY, OF MILWAUKEE, WISCONSIN, A CORPORATION.

ROTARY DISCHARGE FOR CONCRETE MIXERS.

Application filed February 14, 1928. Serial No. 254,259.

The improvements hereinafter described have to do with concrete mixing machines of the type wherein there is employed a rotating, mixing or agitating drum, and appertain primarily to provisions for discharging the contents of the drum after concrete aggregates have been properly admixed therein.

The primary aim of the invention has been to devise improved discharging means, making necessary the application of a relatively small amount of power in order to effect a movement or adjustment of the discharging means so that it may assume either of its two positions in which it controls either discharging or non-discharging actions of the mixing machine or drum associated therewith.

In the carrying out of the invention, I utilize what may be called a floating discharge chute mounted so that it may be brought into frictional engagement with the normally rotating drum, whereby the chute may be driven in a rotative manner by the drum, together with manual or mechanically controlled instrumentalities for initially establishing the frictional connection between the chute and the drum, whereby the former may be driven from the latter.

The invention additionally involves means for automatically disengaging the discharge chute means from the drum or mixer, by which it may be operated in the manner stated in order to discontinue the driving function of the drum in relation to the discharging chute means.

While hereinafter, the discharging means will be characterized as a discharge chute, it is quite within the purview of this invention, that the adaptations thereof as illustrated and described herein, may function for the purpose of controlling charging actions of a drum or receptacle, under which conditions, the term "discharge chute" is used in a relative sense and may be assumed to have a broader significance as covering a chute that may either discharge or charge a receptacle according to conditions of its use.

In the accompanying drawings:—

Figure 1 is a front view, somewhat fragmentary because broken away at different places, showing partially a mixing drum, and discharge chute means of my invention associated therewith.

Figure 2 is a side view also fragmentary

and partially in section, showing the parts 55 that are illustrated in Figure 1.

Figure 3 is a view similar to the lower portion of Figure 1 but depicting the knockout or disengaging means for the chute in a tripped condition ready to perform its chute 60 disengaging function.

Figure 4 is a view somewhat similar to Figure 3, showing the chute in the position it assumes just previous to being tripped to discontinue its movement. 65

Figure 5 is a detailed perspective view of the disengaging device.

Figure 6 is a detailed perspective view of the control member and the actuating parts therefor. 70

Figure 7 is a view similar to Figure 1, but illustrating a different type of means for controlling the engagement or disengagement of the chute from its frictional driving relation, respecting the drum. 75

Figure 8 is a sectional view more fully illustrating the parts depicted in Figure 7, and taken about on the line 8—8 of Figure 7.

Figure 9 is a fragmentary view showing the chute abutment engaging the lifting rollers 80 as when about to be operated to disconnect the chute from the mixing drum.

Figure 10 is a view similar to Figure 9 illustrating the parts in a somewhat more advanced position toward chute disengagement adjustment. 85

Figure 11 is a sectional view taken about on the line 11—11 of Figure 7.

Figure 12 is a fragmentary view showing the lifting rollers in a different position from 90 that previously illustrated.

Referring first to the construction of my invention in Figures 1 to 6 inclusive, the mixing drum is designated A, the discharge at B and the supporting disc or closure plate 95 surrounding the discharge chute, at C. The part C is disposed within the space of a surrounding drip ring 1 such as usually provided at the discharging opening or mouth of a rotating drum type concrete mixer. The chute B is rigid with the disc or plate C and is adapted to assume either of opposite angular positions as illustrated in full and dotted lines in Figure 2, the full line position being that of discharging and the dotted 105 line position that of non-discharging.

The chute device comprising the parts B and C is supported in a floating manner with-

in the drip ring 1 by an arm 2 rigidly connected by a casting or other part with the closure C, said arm 2 being freely pivoted to a shaft 3 carried by brackets 4 or any suitable 5 supporting means on the frame 5 of the machine.

It will be obvious that if the closure disc C is in frictional contact with the drip ring 1, the rotative movement of the drum A, under 10 power of the driving of a suitable engine, may be readily transmitted to the closure member C, and the chute B carried thereby, because the part C has a swiveled connection with the arm 2 and may freely rotate relative 15 thereto as well as rock therewith about the axis of the shaft 3. The swiveled connection just mentioned is shown at 6. Thus, it is, that I use the power of the forces for turning the 20 drum A in order to transmit rotative movements to the chute B through frictional engagement between the parts C and 1. It is only necessary, moreover, that I supply 25 means to connect and disconnect the parts 1 and C in order to control the turning of the chute B from one position to another, or discontinue such turning.

For the last mentioned purpose, I utilize 30 a very simple contrivance including the disengaging device of Figure 5 together with a pair of rigidly attached abutments 7 and 8 applied to the closure or disc C. The disengaging device aforesaid includes a lever 9 having an upper roller 10 and a lower roller 11; also having a disengaging or lifting arm 12. Normally, the disengaging device is in 35 the position of Figure 1 with the lever 9 and arm 12 supported by the latch 13, said latch being pivoted at 14 and having an anti-friction roller 15 at its lower end. The roller 15 40 is engageable by a cam 16 adapted to be rocked with and by a shaft 17 equipped with the handles 18 at its opposite ends. The shaft 17 may be manually operated by the handles 18 or it may be tripped at intervals by some 45 automatic device, such as a batchmeter which is a timing control meter of some mixing machines.

The operation of the construction just 50 described is as follows. Assuming the discharge chute B is in the position of Figure 1, a slight outward pull on the handle 18 will rock the shaft 17, and cam the latch 13 to disengage its nose 13^a from beneath the heel 12^a of the lift arm 12. When so disengaged, the 55 weight of the chute and its closure part C causes it to gravitate by rocking downward of the arm 2 thereby bringing the lower portion of the member C into frictional engagement with the drip ring 1 and causing this frictional engagement to connect the parts 60 1 and C in a driving relation so that the drum turns the chute B and the closure C. Carrying the abutment member 8 upwards in the direction of the arrow of Figure 1, the same 65 action causes the upper abutment member 7

to turn around, and near its lowermost position, it engages the roller 10, rocks the lever 9 upward at its lower end, and re-latches the latch 13 beneath the arm 12. Thereafter, the abutment 7 escapes over the roller 10, rides 70 onto the roller 11 and from the roller 11, up into the seat 12^b of the arm 12. This action is such that the disengaging device of Figure 5 lifts the parts B and C bodily, and stops them from rotating after a half revolution 75 movement is performed. The chute is then in its non-discharging dotted line position of Figure 2. To cause it to assume its discharging position again, the chute 17 is rocked manually or mechanically or automatically, 80 and the same cycle of operation is gone through as just previously described.

As a means for limiting the downward movement of the lower heavier end of the disengaging device of Figure 5, I employ a set 85 screw stop 19 adapted to engage the lower end portion of the lever at a point below the same.

Referring to Figures 7 to 12 inclusive, I utilize much the same construction of chute 90 B' and disc C' as previously described, the latter adapted to frictionally engage the drip ring 1^a for the same purpose as related respecting the first described construction. I provide also upper and lower abutments or 95 arms 7' and 8', but in this instance, the arms 7' and 8' are hook-shaped so to speak, or formed with lifting noses 7'' and 8''. The chute B' and enclosure plate C' may gravitate as previously set forth, and may be 100 mounted by the same supporting means as described. Normally, the parts B', C' are held upwards out of contact or free from the ring 1^a by a latch 20 pivoted at 21 to the frame 22. A pull rod 23 is connected to the latch 21 105 and a spring 24 is interposed between a guide member 25 and a yoke 26 to which the rod 23 is secured and normally holds the rod 23 in the position of Figure 7. The latch 20 has its nose engaging beneath the nose or projection 7'' of the abutment 7' in Figure 7, and thus maintains the parts B' and C' uplifted and disconnected from the drum A at the ring 1^a. A disengaging device is also 110 utilized in this construction and consists of a lever or arm 27 pivoted at 28 to the frame of the machine. Said lever 27 also carries upper and lower rollers 29 and 30 respectively, said rollers being interengaged by means 115 of pinions or gears 31 and 32 integral therewith, or keyed thereto, it makes no difference. The disengaging device lever 27 is upheld by a spring 33, and limited in its upward movement by a projection 34 adapted to engage the 120 frame member 22.

The rollers 30 are capable of engaging with the outer periphery of the drip ring 1^a of the drum A, see Figure 8.

Supposing the parts to be in the position of Figure 7, by pulling out on the rod 23, the 130

latch 20 is disengaged from the abutment 7' permitting the parts B' and C' to lower. This engages the lower portion of the closure member C' with the ring 1^a of the drum A, and the drum thereafter drives the parts B' and C' to rotate them contra-clockwise, as seen in Figure 7. This causes descent of the abutment 7' and ascent of the abutment 8' and the latter when it reaches a point near its uppermost position, engages the lower roller 30, as seen in Figure 9, depresses the lever 27 and roller 30, engaging the roller 30 with the member 1^a on the drum. Thereupon the drum turns the roller 30 and also the roller 29, and the abutment passes from the roller 30 up onto the roller 29, which rollers are now positively driven. The positive drive of the rollers keeps turning the parts B' and C' and also starts to elevate the abutment 8' and the chute B', connected therewith, the actions of the lifting being typified by Figures 9 and 10 of the drawings. After engaging the roller 29, the abutment 8' escapes from the roller so to speak, and engages with the latch 20 which stops the movement of the abutment and likewise, the movement of the parts B' and C' which have been driving said abutment in the operation of the chute. The latch 20 forms a cushioning stop means for completing the lifting or disengagement of the chute B and closure C and discontinuing the turning of the parts in an obvious manner. According to the above, the chute has been turned from the discharging position of Figure 7 to the non-discharging position of the dotted lines of Figure 8, a half revolution movement. The further movement of the chute from non-discharging position to discharging position may be caused by another half revolution going through the same cycle as above set forth, initiating by pulling on the rod 23 again. The rod 23 may be manually or mechanically or automatically operated, as desired.

Having thus described my invention, what I claim as new and desire to secure by Letters Patent of the United States, is:—

1. In a concrete mixing machine, in combination, a mixing drum having an opening for passage of its contents, a chute device associated with said opening for controlling the passage of said contents, means supporting the chute device so that it may move into and out of engagement with the drum whereby to cause movement of the chute device or render it inactive respectively and including a floating mounting for the chute device, abutment means carried by the chute device for normally holding it inactive in relation to the drum, and means cooperating with said abutment means for causing action of the same to effect engagement of the chute device with the drum to turn therewith, and disengagement of these parts.

2. In a concrete mixing machine, in com-

bination, a mixing drum having an opening for passage of its contents, a chute device associated with said opening for controlling the passage of said contents, means supporting the chute device so that it may move into and out of engagement with the drum whereby to cause movement of the chute device or render it inactive respectively, and including a floating mounting for the chute device, abutment means carried by the chute device for normally holding it inactive in relation to the drum, and means cooperating with said abutment means for causing action of the same to effect engagement of the chute device with the drum to turn therewith, and disengagement of these parts, including a disengaging device arranged in the path of the abutment means and operable thereby to cause movement of the chute device out of engagement with the drum.

3. In a concrete mixing machine, in combination, a rotating mixing drum having an opening therein for passage of its contents, a chute device associated with said opening and adapted to engage frictionally with the drum so as to be moved thereby, means for supporting the chute device normally so that it is not engaged with the drum and including abutment devices, means engaging one of the abutment devices normally to maintain the chute device free from the drum and inactive, and control means for releasing the chute device from the action of said active abutment device to effect cooperation of the chute device and drum under predetermined service conditions.

4. In a concrete mixing machine, in combination, a rotating mixing drum having an opening therein for passage of its contents, a chute device associated with said opening and adapted to engage frictionally with the drum so as to be moved thereby, means for supporting the chute device normally so that it is not engaged with the drum and including abutment devices, means engaging one of the abutment devices normally to maintain the chute device free from the drum and inactive, and control means for releasing the chute device from the action of said active abutment device to effect cooperation of the chute device and drum under predetermined service condition, said last named means including a latch adapted to cooperate directly with one of the abutment parts to maintain the chute and the drum free in relation to one another.

5. In a concrete mixing machine, in combination, a rotating mixing drum having an opening therein for passage of its contents, a chute device associated with said opening and adapted to engage frictionally with the drum so as to be moved thereby, means for supporting the chute device normally so that it is not engaged with the drum and including abutment devices, means engaging one of

the abutment devices normally to maintain the chute device free from the drum and inactive, and control means for releasing the chute device from the action of said active abutment device to effect cooperation of the chute device and drum under predetermined service condition, said last named means including a latch adapted to cooperate directly with one of the abutment parts to maintain 10 the chute and the drum free in relation to one another, operating means for the latch to release the abutment device with which it normally cooperates to enable the drum and chute device to cooperate for driving of the latter by the drum, the abutment parts and the chute device so cooperating that the chute device will be automatically rendered inoperative in relation to the drum at a certain point in the revolution of the chute device 20 thereby.

6. In a concrete mixing machine, in combination, a rotary mixing drum having an opening in the side thereof, a chute device mounted in said opening, abutment parts carried by 25 the chute device, a floating mounting for the chute device enabling it to move into and out of engagement with the drum so as to be driven thereby or rendered free therefrom and consequently inactive when so free, a 30 disengaging device cooperative with the abutment parts of the chute device to normally maintain the chute device inactive and free from the drum and latch means associated with said disengaging device causing the same to automatically act in cooperation with the abutment parts to free the chute device from the drum after engagement therewith and having been driven thereby.

7. In a concrete mixing machine, in combination, a rotary mixing drum having an opening in the side thereof, a chute device mounted in said opening, abutment parts carried by the chute device, a floating mounting for the chute device enabling it to move into and 40 out of engagement with the drum so as to be driven thereby or rendered free therefrom and consequently inactive when so free, a dis-

engaging device cooperative with the abutment parts of the chute device to normally maintain the chute device inactive and free 50 from the drum and latch means associated with said disengaging device causing the same to automatically act in cooperation with the abutment parts to free the chute device from the drum after engagement therewith and 55 having been driven thereby, the disengaging means involving a lever, roller devices carried by the lever and engageable by the abutment parts of the chute device and latch means controlling a normally inactive adjustment of 60 the chute device through cooperation with the abutment parts thereof.

8. In a concrete mixing machine, in combination, a rotary mixing drum having an opening in the side thereof, a chute device mounted 65 in said opening, abutment parts carried by the chute device, a floating mounting for the chute device enabling it to move into and out of engagement with the drum so as to be driven thereby or rendered free therefrom 70 and consequently inactive when so free, a disengaging device cooperative with the abutment parts of the chute device to normally maintain the chute device inactive and 75 free from the drum and latch means associated with said disengaging device causing the same to automatically act in cooperation with the abutment parts to free the chute device from the drum after engagement therewith and having been driven thereby, the disengaging means involving a lever, roller devices carried by the lever and engageable by the abutment parts of the chute device and latch means controlling a normally inactive 80 adjustment of the chute device through cooperation with the abutment parts thereof, and trip means for the latch device to release the abutment parts in direct cooperation therewith, at the time therefrom, to enable the engagement of the chute device with the mixing drum.

In testimony whereof I affix my signature.

RAYMOND A. BECKWITH.
